(57) **CLAIM**

The ornamental design for a ceiling fan as shown and described.

DESCRIPTION

FIG. 1 is a top perspective view of a ceiling fan, showing our new design.

FIG. 2 is a bottom perspective view of the ceiling fan of FIG. 1.

FIG. 3 is a top view of the ceiling fan of FIG. 1.

FIG. 4 is a bottom view of the ceiling fan of FIG. 1.

FIG. 5 is a front view of the ceiling fan of FIG. 1.

FIG. 6 is a rear view of the ceiling fan of FIG. 1.

FIG. 7 is a right-side view of the ceiling fan of FIG. 1; and,

FIG. 8 is a left-side view of the ceiling fan of FIG. 1.

Portions of the ceiling fan shown in broken lines form no part of the claimed design. Jagged broken lines on the ceiling fan illustrate a symbolic break in length and form no part of the claimed design.

1 Claim, 8 Drawing Sheets
